(57) **CLAIM**

The ornamental design for an electric coffee grinder, as shown and described.

DESCRIPTION

The patent or application file contains at least one drawing executed in color. Copies of this patent or patent application publication with color drawing(s) will be provided by the Office upon request and payment of the necessary fee.

Figure 1.1 is a top, front, right side perspective view of an electric coffee grinder showing the new design;

Figure 1.2 is a front view thereof;

Figure 1.3 is a right side view thereof;

Figure 1.4 is a rear view thereof;

Figure 1.5 is a top view thereof;

Figure 1.6 is a bottom view thereof;

Figure 1.7 is a top, rear, left side perspective view thereof; and

Figure 1.8 is a left side view thereof.

In the drawings, the portions shown in the color red and the portions shown in broken lines in the color red form no part of the claimed design.

1 Claim, 8 Drawing Sheets
(8 of 8 Drawing Sheet(s) Filed in Color)
